UNITED STATES PATENT OFFICE.

JAMES HALL TAYLOR, OF CHICAGO, ILLINOIS.

PROCESS OF MAKING NOZZLES.

Application filed February 7, 1923. Serial No. 617,534.

My invention relates to a process of manufacturing nozzles such as are commonly used in connection with steam boilers, and it contemplates an improvement over the 5 method, whereby an integral article was formed, set forth in my United States Letters Patent 1,023,228, issued April 16, 1912.

In general, I propose to provide a novel 10 method of forming the flared cross section of the wall of the nozzle or tubular member so as to increase the thickness thereof at the junction with the major flange and the nozzle. So far as the article is concerned, 15 the result is increase of strength at the junction and a more clearly defined line or demarkation between the surface of the major flange and the inner surface of the tubular member. The new method, employed in 20 order to secure this new article, accomplishes its purpose without complicating the patented method of producing an integral nozzle and lies in the manner in which the above results are secured.

25 The process of my invention will be best understood by illustrations showing the results of the various steps in the process.

In the accompanying drawings,

30 Figure 1 is a cross-sectional view of the wrought metal ingot;

Figure 2 is a plan view of the blank after the first step in the process has been carried out;

35 Figure 3 is a diametrical sectional view of the member shown in Fig. 2;

Figure 4 is a view similar to Fig. 3 showing the result of the next step in the process;

Figure 5 is a view similar to Fig. 4 showing the next step in the process;

40 Figure 6 is a plan view of the finished nozzle; and

Figure 7 is a diametrical section of the finished nozzle.

The billet of wrought metal, from which 45 the nozzle is to be formed, is shown at *a*. By the first step in the process this billet is heated and formed, by means of dies, into a circular body *b* having a flange *c* at the top thereof, a circular concentric depression 50 *d* being preferably formed in the top of the body, and a concentric ridge *a'* being formed on the top of the flange, the ridge lying inward of the periphery approximately a distance equal to the depth of the ultimate 55 major flange on the finished article. This is shown in Figures 2 and 3. The blank, at

forge heat, is then subjected to the action of dies which stretch down the middle portion, as shown in Figure 4, so that the body *b* may be brought down and the pocket *d* 60 formed or enlarged to the extent of the pocket shown at *d'*. The result is a tubular part at *c*. That part of the flange *c* lying outside the ridge *a'* becomes the ultimate flange *c'*, while the inner section, since the pocket *d'* tapers downwardly, forms part of the tube *e*, as illustrated. It will be noted that in this section the metal of the ridge is brought down to form the edge *b'* and to make the juncture between the flange *c'* and 70 the tubular member *e* thicker than the lower portion of the wall of the member *e*, as illustrated at *x*. Desirably greater strength at this point is thus obtained, and a desirably sharper edge is secured. The next step 75 in my process consists in flattening down the body *b* so that the flange *f*, parallel to the flange *c'*, is formed. This is illustrated in Fig. 5. It will be noted that here the part *g* may remain and in that event it is removed so that a complete tube may result. The finished product is illustrated in Figures 6 and 7, this article thus comprising 80 the two parallel flanges *c'* and *f* and the tapered connecting tube *e*.

I claim:—

1. The process for forming nozzles which consists in forming a cylindrical body with a flange and a concentric ridge of generally triangular cross-section on the surface of the 90 flange, stretching the body away from the flange inwardly of said ridge and forming a concentric pocket therein, smashing down the body to form a second flange, and removing any remaining metal in line with the 95 pocket to form a complete tube, said ridge producing a greater sectional thickness at the junction of said first flange and the tube, and causing the wall of said tube to be of flaring cross-section. 100

2. The process of forming nozzles which consists in first forming a cylindrical body with a flange and a concentric ridge of generally triangular cross-section on the surface of the flange, then stretching the 105 body away from the flange inwardly of said ridge and forming a concentric pocket therein, then smashing down the body to form a second flange, and then removing any remaining metal in line with the pocket to 110 form a complete tube, the metal in said ridge increasing the sectional thickness of

the tube at its juncture with said first flange and causing the wall of said tube to be of flaring cross-section.

3. The process of forming nozzles which 5 consists in forming a cylindrical body with a flange and a concentric ridge of generally triangular cross-section on the surface of the flange, and forming a tube of that portion of the body inwardly of said ridge, and 10 utilizing the metal in said ridge to reinforce the juncture between said tube and said flange, and causing the wall of said tube to be of flaring cross-section.

4. The process of forming nozzles which consists in forming a cylindrical body with 15 a flange and a concentric ridge of generally triangular cross-section on the surface of the flange, and forming the body within said ridge into a tube so that said ridge will lie at the juncture of the flange and tube 20 and will cause the wall of said tube to be of flaring cross-section.

In witness whereof, I hereunto subscribe my name this 1st day of February, 1923.

JAMES HALL TAYLOR.
